UNITED STATES PATENT OFFICE

DANIEL BAKER DIMICK, OF BIRMINGHAM, ALABAMA

SAND SLINGER

Application filed November 25, 1929. Serial No. 409,661.

The present invention relates to improvements in sand slingers and has for its object to secure the proper adjustment of the path of the sand as it leaves the sand slinger head and travels into the mold.

The object of this invention is to provide an adjustment means for the sand slinger which can be readily applied to existing equipment, which is capable of quick and accurate manipulation to vary the ramming angle at the will of the operator; which comprises adjustable means serving as a stop to limit the swing of the sand slinger for quick and accurate manipulation; which embodies means to positively lock the adjusting means at any angle desired; which provides a powerful drive to enable the heavy sand slinger to be manipulated readily by hand; and which utilizes as the preferred means an eccentric and slide drive underhung below the axis on which the sand slinger is mounted to provide a most conveniently accessible means to rock the apparatus through its angular adjustments about its said axis.

With the foregoing and other objects in view, this invention will be more fully described hereinafter, and will be more particularly pointed out in the claims appended hereto.

In the drawings, wherein like symbols refer to like or corresponding parts throughout the several views:

Fig. 1 is a side elevation illustrating a conventional type of sand slinger equipped with my improved means for mounting and adjusting same.

Fig. 2 is a vertical cross section of the swivel head, by means of which the angle of ram may be shifted as herein described.

Figs. 3 and 4 are cross-sectional views taken respectively on the lines III-III and IV-IV of Fig. 2.

Referring more particularly to the drawings, the sand slinger is mounted on a supporting unit 5 which is suspended on a base, not shown, and is free to revolve in a horizontal plane around the center line of its support. The ramming unit of the sand slinger is suspended on the free end of this

supporting unit 5 and is free to revolve therewith in a horizontal plane.

Sand slingers are usually built with the head 6 so adjusted that the center line D D of the ramming unit is in a vertical plane directly above the center line C C of its supporting unit. 55

The ramming unit 7 is made up of a motor 8, together with connecting shafts to the head 6. The ramming unit as a whole in present sand slingers is connected through the swivel 9 directly to the supporting unit 5 by means of the split clamp 10 securely clamped to the supporting arm 5 by means of the clamp bolts 11. The swivel head, according to my invention, is attached to the supporting arm 5 by forcing one end of a shaft 12 into the open end of the supporting arm 5 and securely fastening it therein, making the hollow supporting arm 5 and the extension shaft 12, for all practical purposes, one piece. The split clamp 10 is clamped to a sleeve 13 by means of the bolts 11. This sleeve 13 is mounted loose on the shaft 12 and is provided with a fork or yoke 14, as shown in Figure 3, in which is shown a sliding block 15. Shaft housings 16 are securely fastened to the shaft 12 in such manner that they will at all times remain stationary in respect to said shaft and its supporting arm 5. The sleeve is free to revolve around shaft 12 unless held by some outside means. 75

An eccentric shaft 17 has a solid bearing 18 in the back shaft housing 16 and a split bearing 19 in the front shaft housing 16. 85 This front split bearing has a taper threaded portion 20 extending beyond and in front of the front shaft housing 16. The eccentric shaft 17 works in the sliding block 15. A taper threaded nut 21 is screwed onto the split bearing 20 and is fastened to the disc 22, to which is attached the handle 23. The hand wheel 24 is securely attached to the outer end of the eccentric shaft 17. Two adjustable stops 25 are clamped to the rim 90 of the hand wheel 24, and a fixed stop 26 is securely fastened to the stationary front shaft housing 16. When the shaft 12 is securely fastened in the supporting arm 5, the shaft 12, shaft housing 16 and the bearings 100

therein must remain in axial relation with the supporting unit 5. With the eccentric shaft 17 in the vertical position shown in Figure 3, the split clamp 10 is fastened with the ramming unit in a position so that the center line D D is directly over and in the same vertical plane with the center line C C of the supporting unit. In this position the sand from the head 6 will be thrown vertically downward.

By means of the hand wheel 24, the eccentric shaft 17 may be turned clockwise, or counter-clockwise, thereby swinging the sleeve 13 and the ramming unit 7 either to the right or left around the center line of the supporting unit 5 as an axis. The swinging of the sleeve and the ramming unit around this axis C C changes the path of the sand as it is thrown from the head 6 on an angle to the vertical. The maximum angle of adjustment is determined by the amount of eccentricity in the eccentric shaft 17. As the stop 26 in the front shaft housing 16 is stationary, an adjustment of the hand wheel stop 25 may be made to limit the travel of the hand wheel 24. When the hand wheel 24 is turned to give the angular adjustment desired, the nut 21 is tightened on the split bearing 20 by means of the disc 22 and the handle 23, causing the split bearing 20 to clamp on the eccentric shaft 17 and securely hold this shaft in the position desired.

In operation, the machine operator determines on the angles to the right and left of vertical which are desired for the particular work he is doing. He adjusts the hand wheel clamps 25 so that when the hand wheel 24 is turned until one clamp 25 is in contact with permanent stop 26, the desired angle to the left of vertical is obtained. The second clamp 25 is adjusted so that when it comes in contact with the permanent stop 26, the desired angle to the right of vertical is obtained.

In the ramming of long patterns, it is desired to throw the sand against the pattern instead of throwing the sand vertically downward. On the same pattern it is necessary to have the sand travel at an angle to the right of vertical when ramming at one place, and at an angle to the left of center at another place. With the adjustable swivel head above described, the operator would unscrew the nut 21, turn the hand wheel 24 to the left until the adjustable stop 25 comes in contact with the permanent stop 26 when he wanted the sand to be thrown at an angle to the left of vertical. He would then tighten the split bearing 20 onto the eccentric shaft 17, holding the sand slinger at this adjustment until another one is desired.

When an adjustment to the right is desired, the operator unscrews the nut 21, freeing the eccentric shaft 17, turns the hand wheel 22 until the other adjustable clamp 25 comes in contact with the permanent stop 26, there-

by throwing the ramming unit over and obtaining the desired angle to the right of vertical as a path for the sand. He then clamps the ramming unit in this position by tightening the nut 21 on the split bearing 20.

The eccentric drive underhung below the supporting unit 5 provides a powerful means for effecting accurate and quick adjustment of the slinger head, thereby enabling such adjustment to be accomplished easily and readily by hand, and moreover the eccentric will serve to hold the head unbalanced to right or left without undue strain on the operator. By mounting the eccentric below the supporting unit the desired amount of leverage can be readily obtained and at the same time the elements for manipulating the sand slinger and for clamping it in adjusted positions are more accessible to an operator standing on the floor.

It is obvious that various changes and modifications may be made in the details of construction and design of the above specifically described embodiment of this invention without departing from the spirit itself, such changes and modifications being restricted only by the scope of the following claims:

What I claim is:

1. The combination with a sand slinger and its support, of hand operated eccentric actuated adjustment means to rock said sand slinger on its support and adjustable stop means to limit its throwing angle to right or left of vertical.

2. In a ramming machine, a sand slinger having a support, leverage means underhung from said support and adapted to rock the slinger about a substantially horizontal axis on said support, and a pair of adjustable stop means to limit said rocking movements.

3. In a ramming machine, a sand slinger having a support, hand wheel adjustment means to rock the slinger about a substantially horizontal axis on said support, and adjustable stop means on said wheel and support to limit said rocking movements.

4. In a ramming machine, a sand slinger, means to mount said slinger to rock on a substantially horizontal axis, hand wheel adjustment means to rock the slinger to permit its ramming angle to be adjusted to right or left of vertical, and quick action clamp means acting on the hand adjustment means to lock the slinger in the desired adjustment.

5. In a ramming machine, a member providing a horizontal supporting axis, a sand slinger mounted to rock about said axis to vary its ramming angle, and an adjustment means comprising a manually operable eccentric and a slide block so carried by said member as to rock said sand slinger.

6. In a ramming machine, a member providing a horizontal supporting axis, a sand slinger mounted to rock about said axis to vary its ramming angle, and an eccentric

- means so underhung from said member as to rock said sand slinger.
7. In a ramming machine, a member providing a horizontal supporting axis, a sand slinger mounted to rock about said axis to vary its ramming angle, a means to rock said sand slinger, and clamp means so engageable with the rocking means as to lock the sand slinger in any desired angular adjustment.
- 10 8. In a ramming machine, a support, a swivel head adjustable thereon, a sand slinger carried by said head and adjustable therewith to vary its ramming angle, and an eccentric and slide drive to adjust the sand slinger.
- 15 9. In a ramming machine, a support, a swivel head adjustable thereon, a sand slinger carried by said head and adjustable therewith to vary its ramming angle, and an eccentric and slide drive underhung from said support and adapted to adjust the sand slinger.
- 20 10. In a ramming machine having a horizontally swinging sleeve support carrying an extension shaft, a sand slinger mounted to rock on said shaft to vary its ramming angle from vertical, a bracket rigidly underhung from said support, and a drive means journaled in said bracket and comprising a crank arm operatively connected to the sand slinger to rock it.
- 25 11. In a ramming machine having a horizontally swinging support comprising an extension shaft, a sand slinger having a swivel support mounted to rock on said shaft to vary its ramming angle from vertical, brackets underhung from said support, and an adjustment means journaled in said brackets and operatively connected to an element underhung from the swivel support for the sand slinger to rock it.
- 30 12. In a ramming machine having a horizontally swinging tubular support, an extension shaft fixed in the free end of said support, underhung bearing brackets fast on said shaft, a sleeve rotatable on the shaft, an eccentric shaft journaled in said brackets, a yoke for the eccentric fast to said sleeve and adapted to be actuated by the eccentric shaft, and means to mount a sand slinger on said sleeve.
- 35 13. In a ramming machine, a swinging arm having a sleeve journaled thereon near its free end, a sand slinger mounted on said sleeve, and means to rock and lock the sleeve, comprising an eccentric shaft, bearings therefor carried by the arm, a yoke coacting with the eccentric and rigidly connected to the sand slinger, a hand wheel to operate the eccentric shaft, a clamp means to lock the said shaft to its bearings, and stop means to limit the hand wheel adjustment.
- 40 14. In a ramming machine, a swinging arm having a sleeve journaled thereon near its free end, a sand slinger mounted on said sleeve, and means to rock and lock the sleeve, comprising an eccentric shaft, bearings therefor

carried by the arm, a yoke for the eccentric rigidly connected to the sand slinger, a hand wheel to operate the eccentric shaft, stop means to limit the hand wheel adjustment, and a clamp nut and split bushing engaged thereby to lock the eccentric shaft and the sand slinger in any adjusted position.

70 15. A ramming machine according to claim 14, in which the clamp nut has an underhung operating handle juxtaposed to the said hand wheel.

In testimony whereof I affix my signature.
